UNITED STATES PATENT OFFICE

2,497,238

BATTERY TERMINAL

Herbert E. Rutherford, Little Falls, N. J., assignor
to International Engineering Associates, Paterson, N. J., a corporation of New Jersey

Application December 26, 1945, Serial No. 637,171

3 Claims. (Cl. 173—259)

1

This invention relates to a battery terminal and it is primarily an object of the invention to provide a device of this kind of a character which permits effective connection of the terminal with both the cable and the battery post without the use of solder or other extraneous media for obtaining the desired connections.

A further object of the invention is to provide a device of this kind wherein the effective mounting of the terminal on a post and the desired securing of a cable to the terminal is accomplished and maintained under the action of a single part mounted on the body of the terminal.

A still further object of the invention is to provide a device of this kind including a terminal body so constructed to enable the terminal to be held to a post and a cable secured to the body under the action of a single nut threading on the body of the terminal.

An additional object of the invention is to provide a battery terminal of a kind that can be readily installed or removed without any particular skill or training and without the use of tools.

The invention also has for an object to provide a battery terminal which will not freeze from corrosion and which is unaffected when coming into contact with the acid or mineral salts of the battery and also wherein is avoided shorts or sudden shocks when contacted by foreign metal such as a tool in the hand of a mechanic.

The invention consists in the details of construction and in the combination and arrangement of the several parts of my improved battery terminal whereby certain important advantages are attained, as will be hereinafter more fully set forth.

In order that my invention may be better understood, I will now proceed to describe the same with reference to the accompanying drawing, wherein:

Figure 1 is a view in perspective of a battery terminal constructed in accordance with an embodiment of the invention;

Figure 2 is a sectional view taken axially through the device as illustrated in Figure 1, an associated cable being shown in fragment and in elevation;

Figure 3 is an elevational view of the terminal end of the cable;

Figure 4 is a view in elevation of the expanding member or wedge unapplied; and

Figure 5 is a fragmentary section substantially on the line 5—5 of Figure 2.

In the embodiment of the invention as illus-

2

trated in the accompanying drawing, A denotes an inner solid member of metal or other material conductive of electricity and which is continued at one end by a thimble shell or skirt 1. Disposed over and encasing the member A and shell or skirt 1 is an outer jacket thimble or shell B, of a non-corrosive and non-conductive material, said thimble shell or skirt 1 and jacket thimble B being flush at their inner or open ends.

The portion 2 of the jacket thimble shell B surrounding the thimble shell 1 is provided with surrounding external threads 3. The portion 2 of the shell B and the shell 1 are provided with diametrically opposed slots 4 and 4', respectively of desired width. The shell 1 and the portion 2 of shell B are tapered from the inner ends of the slots 4 and 4' to have a gradually increasing diameter to the open ends thereof. The material of the shells A and B possesses sufficient inherent resilience to allow the open end portion of the shells A and B, to contract upon the proper application of pressure, but said inherent resiliency tends to constantly expand the tapered portions of the shells to their full diameter when such pressure is relieved.

Threading on the portion 2 of the jacket thimble shell B is a hand nut N of a non-corrosive and non-conductive material, the threaded bore 5 of which being tapered substantially the same as the normal expanded taper of the portion 2 of the shell B. The shell 1 is adapted to fit over the post of a battery and as the nut N is turned to move outwardly toward the open end of the shell B, the portion 2 and shell 1 will be contracted and the shell 1 thus be brought into close clamping engagement with the battery post to provide effective securing of the terminal to the battery post.

The body A across its inner face is provided with a deep straight slot 6 which leads into a bore 6', of circular cross section and with the extremities of which communicate the slots 4 and 4'. At one end the bore 6' is formed to provide a tapered or outwardly expanding part 7 with its larger end 7' outermost or immediately adjacent to the shell B which overlies and closes said tapered outer end 7 of the bore.

The body of the shell B at the inner end portion of the slot 4' remote from or opposed to the taper 7 is provided with an opening 7' of a diameter in excess of the diameter of the bore or passage 6'.

The bare extremity of a cable C is inserted through the opening 7' and is forced through the bore 6'. Before insertion, said end of the

cable C has pressed therein the pointed end of a wedge member 8 and as the cable C is forced through the bore 6', the wedge member 8 will contact the wall of bore 7 or that portion of the shell B disposed over the expanded end 7 of the bore 6', so that by continued forcing of the cable into the bore 6' toward the shell wall, the wedge will be pressed against the shell wall and forced into the extremity of such cable which will be expanded and be effectually held against withdrawal.

It is also to be pointed out that as the nut N is turned to clamp the terminal to a battery post, the resultant contraction of the shells 1 and B, will also contract the slot 6 and the parts 6', 7 and 7' to effect clamping engagement of the terminal with the cable C and thus further assure an effective securement of the cable C to the terminal.

From the foregoing description it is believed apparent that the terminal as herein embodied can readily be applied or removed by an unskilled person as it is only necessary to properly turn the hand nut N without the use of a tool. From the foregoing description it is thought to be obvious that a battery terminal constructed in accordance with my invention is particularly well adapted for use by reason of the convenience and facility with which it may be assembled and operated.

I claim:

1. A battery terminal comprising a shell open at one end and fitting over a battery post, the open end portion of the shell being outwardly flared, said flared portion having slots extending therealong to permit said portion to be contracted, a member surrounding said flared portion and movable therealong to contract said portion, the shell at the inner ends of the slots being provided with a transverse bore communicating with said slots, one end of the bore being closed, said bore being adapted to receive from its other end an extremity of a current conducting cable, the bore at the closed outer end being of gradually increasing diameter for a portion of its length, and means for expanding the end of the cable entering the said portion of the bore from the said open end thereof.

2. A battery cable terminal adapted to engage a battery post, comprising a thimble shell

formed to receive the battery post, the shell having opposite longitudinal slots from the open end thereof opening at their inner ends into a bore formed transversely across the closed end of the thimble shell, the bore opening through a slot into the interior of the thimble shell, a jacket thimble of insulation material encasing the thimble shell and having slots corresponding to and matching the slots of the thimble shell, one of the slots of the jacket thimble opening at its inner end into an opening aligning with an end of the cable receiving bore, the jacket thimble at the opposite end of the bore covering such end of the bore, and means encircling the slotted portions of the thimble and jacket thimble for effecting the contraction of such portions into gripping relation with an inserted battery terminal post.

3. A battery cable terminal of the character stated in claim 2, wherein said thimble and jacket thimble are tapered from the inner ends of the slots to the open ends of the thimbles to have a gradually increasing diameter to the open ends, said jacket thimble being exteriorly screw threaded through the tapered portion, and the said means for contracting the thimbles comprising a nut encircling and in threaded connection with the threaded portion of the jacket thimble.

HERBERT E. RUTHERFORD.
